UNITED STATES PATENT OFFICE.

CHARLES D. JENKS AND HUBERT M. PERRY, OF CHICAGO, ILLINOIS, ASSIGNORS, BY
MESNE ASSIGNMENTS, TO SOPHIE L. WOODS, OF CHICAGO, ILLINOIS.

ANTIFRICTION BEARING.

Application filed March 15, 1915. Serial No. 14,329.

To all whom it may concern:

Be it known that we, CHARLES D. JENKS and HUBERT M. PERRY, citizens of the United States, and residents of Chicago, in

5 the county of Cook and State of Illinois, have invented certain new and useful Improvements in Antifriction Bearings; and we do hereby declare that the following is a full, clear, and exact description thereof, 10 reference being had to the accompanying drawings, and to the letters of reference marked thereon, which form a part of this specification.

This invention relates to improvements 15 in antifriction bearings and more particularly to such bearings as are adapted for use as side bearings for railroad cars. The invention consists of the matters herein-after described and more particularly pointed out in the appended claims.

In side bearings for railroad cars as more usually constructed the bearing plate or bar on the truck is apt to bring the greater part of its force to bear on one part of the 25 roller owing to the fact that the roller is cylindrical in construction instead of conical with the result that the roller is subjected to unequal wear on the surface and in addition, owing to the inequality of the 30 load distributed over its surface, is not capable of performing adequately or completely its function as an anti-friction device. The object of our invention is to provide an anti-friction device of simple and economical construction in which the load will 35 be transmitted as formerly over the full length of the anti-friction roller no matter how much the body bolster may be tilted with reference to the truck bolster. The 40 advantages of our invention will appear more fully as we proceed with the specification.

In the drawings:

Figure 1 is a view representing a side 45 elevation of our improved anti-friction device.

Figure 2 is a view representing an end elevation of the same.

Figure 3 is a view representing a longitudinal vertical section through the bearing 50 in the plane indicated by the line 3-3 of Figure 2.

Figure 4 is a view representing a top plan view of our improved anti-friction device.

55 Figures 5 and 6 are views representing

respectively vertical transverse sections through the anti-friction device in planes indicated respectively by the lines 5-5 and 6-6 of Figure 3.

Referring now to that embodiment of 60 our invention illustrated in the drawings, 10 indicates as a whole the casing and 11-11 the anti-friction rollers contained within said casing. The anti-friction device as illustrated herein is of the type that 65 is adapted to be attached to the truck bolster. 12 indicates the truck bolster in Figure 1 and 13 the bearing plate or bar on the body bolster which is adapted to engage with the anti-friction rollers when they 70 are transmitting a load.

Casing 10 consists of the base plate 14 which is adapted for attachment to the truck bolster and of an oblong rectangular shell 15 which contains the anti-friction 75 rollers and through the open side of which said anti-friction rollers project for bearing engagement with the wear plate or bar 13 on the body bolster.

The base plate 14 is provided with four 80 upstanding flanges 16, which are placed at each side and near the end of the shell 15, and has between said flanges a bearing surface 17 on which the shell 15 rests. Said bearing surface is inclined each way from 85 a longitudinal median line toward the upright flanges 16 so that it provides a surface upon which the said shell 15 may rock. The shell 15 has side walls 18-18, end walls 19-19 and a bottom wall 20, the latter 90 having a flat surface 21 spaced upon the surface 17 of the base plate 14. The shell 15 also has an intermediate dividing wall 19^a which in the example of the invention 95 illustrated divides it into two compartments one for each of the two anti-friction rollers 11 contained in said shell, and as many or as few of said anti-friction rollers may be used as desired, each roller being preferably confined in its own compartment in the shell. 100

The side walls 18 are preferably thickened as indicated at 22 in the neighborhood of bearings of the anti-friction rollers. Each anti-friction roller 11 is mounted on a short shaft 23 on which it has rotative bearing 105. The shaft 23 itself is mounted in suitable apertures formed in the thickened parts 22 of the side walls 18 of the shell 15 and is retained therein in any convenient manner.

As shown, the said shafts are cut away at 110

each end as indicated at 24, and after they are placed in the apertures formed in the thickened part 22 to receive them, the metal of said parts is hammered in as indicated 5 at 25 to engage the ends of the shaft and thus retain them in position. By this construction the load is transmitted from the body bolster in the anti-friction roller and from said roller through its shaft 23 to the shell 15. Manifestly if the load tends to be greater toward one end of the roller than the other, the shell will be caused to rock on its bearings on the surface 17 of the base plate so as to assume, for example, the position shown in dotted lines in Figure 5. The position shown in Figure 5 is, of course, exaggerated more than usually occurs, and is simply shown in this way to illustrate the action of the device. Manifestly in the construction described the load will always be transmitted evenly over the surface of the anti-friction roller.

The shell 15 is provided at its ends with round stub shafts 26 which are engaged in 25 bearings formed by flanges 27 at the ends of the base plates which are bent about said stubs when the shell is placed in position on the base.

The end walls 19-19 of the shell 15 and 30 the intermediate dividing wall 19^a are cut away at the bottom to provide ventilating openings 28 so that dust, cinders, water and the like may escape from the shell endwise thereof. In addition, the said walls 18-18 35 of said shell are provided with ventilating openings 29-29 at either side of the intermediate dividing wall 19^a. By means of these openings free ventilation of the shell is secured.

40 While in describing our invention we have referred to certain details of mechanical construction and arrangement, it is to be understood that the invention is to be in no way limited except as pointed out in the 45 appended claims.

We claim as our invention:

1. In an anti-friction side bearing, a bearing member, a roller carrier mounted on said bearing member, the said roller carrier and the said bearing member having opposed, relatively divergent surfaces adapted to provide a free rocking movement of the roller carrier on the bearing member, and means connecting said roller carrier and said bearing member adapted to hold them in co-operative relation but permitting a free rocking movement of the carrier upon the bearing member.

2. In an anti-friction side bearing, a bearing member, a roller carrier mounted on said bearing member, the said roller carrier and the said bearing member having opposed, relatively divergent surfaces adapted to provide a free rocking movement of the roller carrier 60 on the bearing member, the horizontal area of

the said bearing surfaces approximating the plan area of the roller carrier, and means connecting said roller carrier and said bearing member adapted to hold them in co-operative relation while at the same time permitting a free rocking movement of the roller carrier upon the bearing member. 70

3. The anti-friction side bearing comprising a bearing member having a bearing surface inclined downwardly in each direction 75 from a longitudinal median line, a roller carrier having a substantially flat bearing surface engaged upon the bearing surface of the bearing member, said carrier member and bearing member being connected to permit a free rocking movement of the carrier member on the bearing member about the said median line of said bearing member, and an antifriction element journaled in said carrier member with its axis of rotation 80 extending at right angles to the said median line.

4. An anti-friction side bearing comprising a base plate, an open top shell having sides, ends and a bottom wall, said shell and base plate having opposed, relatively divergent surfaces providing a free rocking movement of the shell on the base plate, an antifriction element rotatively mounted in said shell and projecting through the open 90 top thereof, and means connecting said shell and said base plate to retain them in operative relation but permitting a free rocking movement of the shell upon the base plate. 95

5. An anti-friction side bearing comprising a base plate, having upright flanges thereon, said base plate having a top bearing surface intermediate said flanges, an open top shell having sides, ends and a bottom wall, said bottom wall having a bearing surface which rests on the top bearing surface of said plate, the two bearing surfaces being relatively divergent to provide a free rocking movement of the shell upon the base plate, an antifriction roller projecting through the top of the said shell, a transverse shaft mounted in said shell and providing rotative bearing for said roller, and coacting devices on said base plate and shell adapted to retain the shell in operative engagement with the base plate but permitting a free rocking movement of the shell upon the base plate. 100 110 115

6. An anti-friction side bearing comprising a base plate having upright flanges thereon, said base plate having a top bearing surface intermediate said flanges, an open top shell having sides, ends and a bottom wall, said bottom wall having a bearing surface which rests on the top bearing surface of said plate, the said two bearing surfaces being relatively divergent to provide a free rocking movement of the shell on the base plate, antifriction rollers projecting through the open top of the said shell, transverse 120 125 130

shafts mounted in said shell and providing rotative bearing for said rollers, and co-acting devices mounted on said base plate for holding the two in co-operative relation, at 5 the same time permitting a free rocking movement of said shell on said base plate.

7. An anti-friction side bearing comprising a base plate having a top bearing surface inclined downwardly in each direction 10 from a median line, a shell mounted on said base plate, said shell having a flat bottom adapted for free rocking bearing engagement upon the bearing surface of said base plate, antifriction rollers mounted in said 15 shell and arranged parallel to the direction

of rocking movement of said shell on said base plate, and coacting means on said shell and base plate preventing lateral or longitudinal shifting movement of said shell on said base plate but permitting a free rocking 20 movement of the shell on the base plate.

In testimony that we claim the foregoing as our invention we affix our signatures in the presence of two witnesses, this 29th day of October, A. D. 1914.
